[57] CLAIM

The ornamental design for a recreational equipment device, as shown and described.

DESCRIPTION

FIG. 1 is a front perspective view of our recreational equipment device;

FIG. 2 is a rear perspective view thereof;

FIG. 3 is a top plan view thereof;

FIG. 4 is a bottom plan view thereof;

FIG. 5 is a left end elevational view thereof;

FIG. 6 is a left front side elevational view thereof;

FIG. 7 is a right front side elevational view thereof; and,

FIG. 8 is a right end elevational view thereof.

The broken line showing in FIGS. 1 and 2 is for illustrative purposes only and forms no part of the claimed design.
